TROLLEY HOIST

Ragnar A. Norbom, Clifton, N. J., assignor to
Motor Terminals Company, New York, N. Y., a
corporation of Delaware

Application May 29, 1934, Serial No. 728,089

16 Claims. (Cl. 212—11)

This invention relates to a traveling crane having four depending cables arranged in pairs and adapted to suspend a load at four spaced points, raise it and transport it, and particularly such a crane combined with means for laterally shifting either pair of the cables relative to the other pair. Such a mechanism is very useful in transferring demountable bodies from one vehicle to another, as it enables substantially vertical cables to readily be engaged to a demountable body standing obliquely to the crane support. The invention enables the body to be lowered directly into engagement with a truck frame, for instance, or raised vertically therefrom, though the frame be at somewhat of an oblique angle to the normal position of the cables.

One of the objects of the invention is to provide a hoisting and trolleying mechanism which shall be extremely flexible in operation, to the end that bodies may be readily transferred one vehicle to another even though such vehicles stand obliquely to each other and to the normal position of the traveling crane. I accomplish this by employing two frames directly supported by independent crane trackways and interconnected by a comparatively light bridge, each of the frames being independently movable relative to each other and to the bridge, and carrying a substantially standard driving axle construction similar to those of automobile trucks but with cable drums in place of the usual automobile wheels and with the differential blocked to prevent independent movement of the axle sections. A motor is mounted on the bridge and drivingly connected with each of the blocked differentials.

My invention is in the nature of a modification of, or improvement on, a weaving traveling crane of Benjamin F. Fitch, for which application Ser. No. 727,320 was filed on May 24th, 1934 and assigned to my assignee, Motor Terminals Company. Reference is made to the patent to be granted on that application for claims which may apply to both the embodiment there shown and the embodiment of this application.

My invention is illustrated in the drawings hereof, is hereinafter more fully explained in connection therewith, and the essential novel characteristics are set out in the claims.

In the drawings Fig. 1 is a plan partly broken away of a traveling crane embodying my invention; Figs. 2 and 3 are vertical sections thereof on the lines 2—2 and 3—3 respectively in Fig. 1; Fig. 4 is an end view partially in section; Figs. 5 and 6 are vertical sections on the planes indicated by the lines 5—5 and 6—6 on Fig. 4 but on a ma-

terially larger scale; Fig. 7 is a horizontal section on the plane indicated by the line 7—7 on Fig. 4 but on a larger scale; Figs. 8 and 9 are details illustrating the connection of the bridge with the individual trolley hoists, being respectively a plan of parts illustrated on a smaller scale in Fig. 1 and a section on the line 9—9 on Fig. 8; Fig. 10 is a diagrammatic end elevation illustrating the hoisting mechanism in the act of raising a demountable body from a highway truck; Figs. 11, 12 and 13 are diagrams illustrating a barrel controller which might be used to control the propelling motors for trolleying and weaving, Fig. 11 being a plan of the controller, Fig. 12 being a fragmentary vertical section therethrough, as indicated by the lines 12—12 on Fig. 11, and Fig. 13 being a diagram of the electrical circuits.

In the drawings, 10 and 11 indicate a pair of parallel supporting rails shown as of I-beam form. These rails may be carried in any suitable manner, as suspended from a stationary structure or from the top of a gantry. Directly beneath each rail and parallel therewith is a horizontal channel-shaped beam 12 with its flanges facing downwardly, which forms the main frame for the dual hoist associated with that rail. Rigidly secured to the channel beam are standards 13 which extend upwardly from its opposite sides and rotatably carry studs 20 on which are secured wheels 21 which ride on the lower flanges of the I-beam rails.

As illustrated more particularly in Fig. 6, each standard 13 comprises an angle piece 14 riveted, bolted or welded to the upper face of the channel web, an outer vertical plate 15 and intermediate vertical filler pieces 16, all secured together as by bolts and nuts 17. The two spaced members 14 and 15 provide ready means for supporting a pair of ball bearings 19, Fig. 6, in which the rotary shaft 20 is journaled.

Secured to the side flanges of each channel beam 12 and depending therefrom are brackets 30 (Figs. 1 and 4), which are provided with bottom caps 31 and bolts 32 by which they embrace and support the housing 40 of the automobile-like driving mechanism. Suitably mounted in each housing 40 are a pair of aligned shafts, one of which is shown at 42 in Fig. 7. These shafts at their adjacent ends are rigidly connected with a suitable gear as for instance a bevel gear 45, (shown in dotted lines in Fig. 4), with which meshes a bevel pinion 46 on a driving shaft 47, though a worm and worm wheel may be employed in place of the bevel pinion and bevel gear if desired. In either case this reduction gearing is 55

mounted in a central enlargement 41 of the housing.

Rotatably mounted on the end portions of the housing 49 are sleeves 50 (Figs. 4 and 7), supported by roller bearings 51 between the sleeve and the housing. The end of the sleeve is connected to a head 49 on the driving shaft 42, all after the manner of automobile construction.

The driven sleeve 50 has an external annular flange 53 which is bolted to a flange 63 on a cup 60, which extends over the end of the driving axle and terminates in a coupling 64, which is connected to a short shaft 65. This shaft 65 is supported in suitable bearings carried by standards 66 secured to the channel beam 12 and depending therefrom. Between these standards a cable drum 70 is rigidly mounted on the shaft 65. A lifting cable 71 is attached to the drum and makes several turns about it and depends therefrom either directly to the load or to a cradle which may be attached to the load, as desired.

The construction described provides a dual hoist adapted to raise two cables 71 in unison whenever the driving shaft 47, journalled in the central portion of the housing, is rotated.

The two dual hoists are identical, and are both connected in the same manner with an intermediate bridge, which extends from one dual hoist to the other. The connection between the hoists and the bridge is such that each hoist unit may be moved independent of the bridge and the other hoist unit. This bridge, which may be of light construction as it does not carry any of the load to be lifted, as shown in Figs. 1 and 2, comprises a pair of side members 80, extending from beneath one crane trackway to beneath the other, cross-beams 81 connected to such side members near either end, and a pair of intermediate cross beams 82. At each end of the bridge the members 80 extend beyond the cross beams 81 and are movably connected to the channel beam of the respective dual hoist at that end, as will be hereinafter more fully described. The bridge is preferably also braced by diagonal bars 87 leading inwardly from the four corners to the transverse beams 82 adjacent their centers, as indicated in Figs. 1 and 2.

At each end of the bridge where the cross beams 81 are located, each side bar 80 is extended by an inverted channel member 86, to which is secured a suitable downwardly extending stud 90 (Fig. 9) on which is mounted a horizontally extending roller or bushing 92 which enters a slotted opening 93 in the channel beam 12 of the respective hoist unit. The lower face of the bushing 92 extends beneath the lower edge of the stud 90 and engages a bearing plate 94 which is welded or otherwise secured to the underface of the channel beam 12. The rollers or bushings 92 are slightly less in diameter than the width of the slots 93 and of slightly greater thickness than the web of the channel beam 12.

The slots 93 in which the circular bushings 92 seat provide a grease pocket and the bushing, held in position by the weight of the bridge, provides a frictional contact between the four corners of the bridge and the trolley hoists and act as floating bearings, in case of cramping of the bridge, thereby decreasing the trolleying resistance due to diagonal strains on the structure. The slots 93 are preferably positioned in alignment with the web of the trolley hoist supporting beams 10 or 11 and thereby so distribute the weight of the bridge on the trolley hoist mechanism as to prevent canting or tilting of the hoist.

To operate the two shafts 47, the rotation of which will turn the four drums and actuate the four cables, I provide a suitable motor 100 supported by the transverse bridge beams 82, having its armature connected to a worm 101 (shown in dotted lines in Fig. 1), which meshes with a worm wheel beneath it, shown at 102 in dotted lines in Fig. 2 and contained within a casing 103. This worm wheel is on a shaft 104 journalled in the casing, and extending in each direction therefrom. On each side the shaft 104 is connected by a universal joint 110 to a shaft 111, which has a telescopic connection with an aligned shaft 112, which latter is connected by a universal joint 113 to the shaft 47, at that side of the crane. The universal and telescoping connection described enables the motor 105 to drive the reduction gearing on either side which shifts relative to the bridge.

To move each dual hoist a motor is mounted thereon geared with one pair of supporting wheels. Thus, as shown in Figs. 1, 4 and 5, the motor 120 is rigidly secured to the underside of the channel beam 12 near its end. On the armature shaft 121 of this motor is a worm (not specifically shown) which meshes with a worm wheel, indicated in dotted lines at 122 in Fig. 5 and rigid on a shaft 123, which has bearings in a casing 124 surrounding the worm wheel and worm and furnishing means for attachment of the motor to the hoist frame 12. Rigid on the shaft 123 are pinions 125 which mesh with idlers 126, which in turn mesh with gears 127, which are rigid on shafts 128 carrying wheels 129 which rest on the lower flange of the supporting rail 10 or 11.

The idler and driven gears just described are carried by suitable standards secured to the frame and channel beam 12. Like the standard 13 heretofore described, this standard comprises an angle piece 130, secured to the channel beam, spaced filler pieces 131 secured to the upright flange of the angle piece, and an external plate 132 secured to the filler piece. The gears 126 and 127 lie within the space between the two filler strips 131. The intermediate gear 126 is shown as carried by a stud 135 mounted in the external plate 132. The upright flange of the angle piece 130 and the vertical plate 132 carry suitable ball bearings 137 in which the shaft 128 is rotatably journalled. The driving wheels 129 are so arranged as to receive sufficient load to cause them to coast with the flange of the beams 10 or 11 under all conditions. If desired, this may be accomplished by slightly lowering the center of the wheels 129 relative to the wheels 21, or by slightly increasing the diameter of the wheels 129 over the diameter of the wheels 21.

The construction described enables the motor 120 when energized to drive the wheels 129 through suitable reduction gearing to propel the dual hoist mounted on the channel beam 12.

When the crane is to be trolleyed for a material distance, either with or without a load supported thereby, the two motors 120 are preferably operated in unison in one direction or the other according to the direction of travel desired. When, however, it is desired to shift the cables at one end with reference to those at the other, to enable ready cooperation with a body out of exact registration, one of the motors is operated alone, and this shifts the dual hoist associated with that motor, with reference to the bridge and the other hoist. However, if it is desired to shift the cables at one end in a forward direction and the cables at the other end in a reverse direction,

one of the motors is operated in a reverse direction while the other motor is operated in a forward direction; this shifts one hoist forward and the other hoist rearward relative to the bridge.

5 The weaving operation just described, which is limited by the distance which the rollers or bushings 92 may travel in the slots 93 of the frame standards, enables the depending cables to be brought into accurate registration with a body 10 somewhat out of parallelism with the bridge, but does not interfere with the general trolleying of the crane by its two motors, or with the raising or lowering of the load by the motor 100.

As heretofore stated, the cables 71 may depend directly to the load or to a cradle which engages the load. As illustrated in Fig. 3, I have provided a cradle 140 in the form of a rectangular frame having sheaves 142 about which the cables pass in bights, the free ends 72 of the cables being attached to the dual hoist frame by brackets 73. Suitable shackles 145 which may depend from the journal bolts 146 of the sheaves furnish ready means for engaging the demountable body.

As illustrated in Fig. 10, B indicates a demountable body adapted to be mounted on a suitable highway truck C. This body may be provided with sockets b in its floor frame, adapted to coact with projections c on the truck to prevent lateral displacement of the body when mounted. At its eaves the body is provided with hooks b', which are adapted to be engaged by the depending shackles 145 of the floating frame 140.

It will be seen that when a truck having the body just described is driven into place beneath and approximately registering with the bridge and the cradle lowered, the shackles may be accurately presented to the hooks by operating either one of the motors in one direction or the other to shift the two cables at that end relative to the other two, or by operating one motor in one direction and the other motor in the opposite direction.

It will be noticed that the lifting stresses on the cables 71 are carried directly to the dual hoist beam 12 and thence by the supporting wheels to the I-beam trackway 10 and 11 without throwing any stresses on the bridge. The bridge merely supports the raising motor and its immediately driven mechanism and serves to keep the two dual hoists approximately opposite each other while allowing the slight weaving movement desired.

Any suitable arrangement of switches may be employed for controlling the two propelling motors, Nos. 1 and 2. Preferably, however, there is suitable means for controlling the two motors together for ordinary trolleying, and a separate control for each motor for use in weaving alone. I have illustrated in Figs. 11, 12 and 13 suitable means for this purpose in the form of a pair of independently operable drum controllers and an associated controller arranged to operate both drums in unison, but the electric connections may be made by means of push buttons or other form of switches, as desired.

Briefly, as illustrated in Fig. 13, the two motors, Nos. 1 and 2, each have their armature circuits A and field circuits F terminating at a set of contact fingers G, each set of which also includes terminals of the main lines indicated by + and -. On each rotatable barrel H and J are two rows of 70 contact plates K and L, which are adapted to coact with the contact fingers of their respective motors independently and control the motors for "Ahead" or "Reverse", as indicated, each barrel being given positions indicated by a suitable handle M, Fig. 11. Thus, each motor may be op-

erated independently of the other to facilitate operation of the hoists, especially during the weaving operations.

A third controller handle N is provided to enable the operator to control both motors as a unit during normal trolleying of the hoist. As shown in Figs. 11 and 12 the handle N is secured to a shaft 150 slidably mounted for movement parallel with the axis of the controller drums. Rigidly secured to each controller drum is a gear 151 both of which are arranged to be simultaneously engaged by a gear 152 carried by the shaft 150, consequent upon the depression of such shaft, thereby connecting both controller drums for operation as a unit by the handle N. Suitable interlocking cams 153 carried by the drum shafts are arranged to coact with a coacting interlocking cam 154 carried by the shaft 150 and are provided with recesses 155 which permit the sliding of the shaft 150 only when the drum controllers are in their "Off" position, thereby preventing damage to the parts.

It will be seen, from the description given, that I have provided a very effective hoisting mechanism adapted for raising a demountable body with its load under electric power or lowering such body onto a vehicle; while, without the necessity of any additional motor mechanism, I have provided weaving means to enable the ready registration of the lifting cables with a body which is not accurately positioned with reference to the crane trackway. The construction adapts itself for manufacture from standard structural members, standard motors, and standard driven parts of demonstrated automobile usage. The crane, being underslung from the supporting tracks, may be readily lowered to the ground for repair whenever occasion arises.

I claim:

1. The combination of two trolley hoists mounted side by side on parallel tracks, two motors for operating the trolleying mechanism of the hoists respectively, means located at a common point for controlling both motors as a unit in the same direction of travel or independently in opposite directions, or alone.

2. The combination of two dual trolley hoists mounted side by side on parallel tracks each having a pair of winding drums and driving mechanism therefor, a pair of electric motors associated with the respective hoists for trolleying the same, and means located at a common point for controlling the two motors as a unit or either of the motors alone as desired.

3. The combination of two dual trolley hoists each comprising a beam, means for movably suspending it beneath an overhead trackway, an electric motor on each beam adapted to operate the trolleying mechanism thereof, hoisting mechanism carried by each beam and having a pair of cable drums spaced apart and driving mechanism between the drums including a gear, a bridge connected with the two beams and comprising a pair of spaced beams suitably braced, a driving motor mounted on the bridge, driving mechanism leading from said motor to the said gears of the respective dual hoists, means connecting said bridge beams at one end to the frame of one of the hoists, a pair of downwardly extending members carried by the respective bridge beams at their other ends and engaging horizontally extending recesses in the other hoist frame beneath its supporting trackway, and means for controlling one of the trolleying motors independently of the other.

4. The combination of dual trolley hoists each comprising a beam having a horizontally extending web having longitudinally extending slotted recesses therein, means for movably suspending it on an overhead trackway, means on each beam adapted to operate the trolleying mechanism thereof, hoisting mechanism carried by each beam, said trolleying mechanism and said hoisting mechanism being suspended from said beam 5 and in vertical alignment therewith, a bridge interconnecting said hoists, the connections between the bridge and each hoist including a downwardly extending pin, a bushing rotatably mounted on said pin and having its periphery spaced 10 apart from the side and end walls of said recess and its lower face in engagement with said beam and its upper face in engagement with said bridge, whereby said bridge and beam are spaced apart 15 from each other but movement therebetween is limited to a predetermined amount.

5. The combination of two trolley hoists, each having a frame and means for suspending it beneath a supporting trackway, a pair of electric motors associated respectively with said hoists 25 for trolleying them, a bridge interconnecting said hoist frames and supported thereby and having a sliding frictional contact with at least one of said frames in vertical alignment with the supporting trackway, allowing movement in the direction of travel of such hoists.

6. The combination of two dual trolley hoists mounted side by side and each having its own frame and means for suspending it beneath a trackway, a pair of cable drums spaced apart 35 and driving mechanism between the drums on each frame, a bridge connected with the two hoist frames and comprising a pair of spaced beams with transverse beams connected to them, a driving motor mounted on the bridge, power-40 transmission mechanism leading from said motor to the driving mechanism of the respective dual hoists, and means connecting said bridge beams at one end to the frame of one of the hoists, said bridge beams overlying the frame 45 of the other hoist beneath the trackway centrally thereof and in such region slidably connected with and supported by the last mentioned frame.

7. A hoisting mechanism adapted to be suspended from a pair of overhead trackways, each 50 trackway including a vertical beam having a central vertical web with outwardly extending flanges, a trolley hoist mechanism carried by each trackway and suspended therebeneath, each trolley comprising a longitudinal beam beneath its 55 respective trackway, and spaced therefrom, brackets carried by said beam and wheels mounted on said brackets and engaging opposite flanges of the trackway, a hoisting unit suspended beneath each beam, a bridge interconnecting the beams of both of said trolley hoists, the connection between one of said beams and the bridge comprising a member projecting between the beam and its respective trackway, and means 60 interconnecting the beam and bridge to permit a limited movement therebetween, said last named means being positioned in vertical alignment with the web of the respective trackway.

8. In combination, a pair of trolley hoisting 70 mechanisms centrally suspended from overhead parallel track members, a bridge member spanning both mechanisms and having a floating connection with one of them bearing on the same in substantially vertical alignment with the axis of the track member thereof, and power mecha-

nism on the bridge member with connections for driving the hoisting mechanisms.

9. The combination of two trolley hoists, each having its own frame, a bridge supported by the frames of said hoists, and supporting, guiding and floating connections with each of the hoists at two spaced regions longitudinally of the hoists, said connections including limiting means to allow limited independent movement of each hoist with reference to the bridge.

10. In combination with two independently movable parallel spaced trolley hoists, each having its own frame, a bridge having floating linear guiding connections with both frames, spaced in the direction of travel of the hoists so as to maintain the various parts of the bridge at all times substantially parallel to the hoists and to maintain a four point suspension for the bridge.

11. In hoisting mechanism, two independently movable laterally spaced parallel trolley hoists, 20 each having a frame and raising mechanism, a bridge spanning the hoists, means supportingly and floatingly connecting the bridge to both frames at two regions of each spaced longitudinally of the direction of trolleying of the hoists, 25 and power mechanism on the bridge intermediate of said regions and having flexible driving connections with the raising mechanisms of the hoists.

12. The combination of two trolley hoists having individual frames and adapted to operate on parallel trackways, a transverse bridge extending between the trackways and connected with and supported by the frames of the two hoists, the connection to each of the hoists being in spaced 35 regions longitudinally of the trackways said connections including relatively slidably supporting members on the bridge and hoists adapted to allow limited independent movement of both hoists relative to the bridge in the direction of travel of 40 the hoists, and independent means for operating the trolleying mechanism of said hoists respectively.

13. The combination of a pair of dual hoists adapted to be mounted on parallel trackways, 45 each hoist frame comprising a longitudinal beam, means for suspending it from the corresponding trackway, raising mechanism on the underside of the beam, a transverse bridge, and means supporting and connecting the same at two longitudinally spaced points with each of the two beams, the connecting means including relatively slidably coacting members on the bridge and beams arranged to allow limited independent movement between the connected parts, a motor on the 55 bridge, reduction gearing driven thereby, and shaft mechanism connecting the reduction gearing with the raising mechanism of the two hoists, the shaft connection employing telescopic shafts and two universal joints.

14. The combination of two dual trolley hoists, each having its own frame carrying a pair of cable drums and driving mechanism for rotating them as a unit, a bridge spanning the two hoists, floating guiding connections between the bridge 65 and each of the hoists, means to limit the floating movement between the bridge and hoists, electric motor mechanism on the bridge connected with the driving mechanism of both hoists, individual trolleying mechanism for the respective hoists and 70 a pair of electric motors located on the respective hoist frames for operating the trolleying mechanism thereof, means for controlling both motors as a unit in the same direction, means for controlling each of said motors alone, and means for 75

operating one of said motors in one direction while the other motor is being operated in a reverse direction.

5. 15. In a dual trolley hoist, comprising two hoisting units each having a frame, and means for suspending the frames from respective overhead trolley tracks, a bridge connecting the two frames, and a connection between the bridge and one of said frames permitting movement of one frame with reference to the other longitudinally of the tracks, said connection comprising an elongated upwardly open recess on one frame and a guiding device on the bridge slidably occupying the recess, said recess forming an oil retaining pocket to lubricate the guiding device.

16. In combination, a pair of trolley hoisting mechanisms respectively centrally suspended from overhead parallel track members, a bridge member spanning both mechanisms and having a floating connection with one of them, said floating connection including means on the bridge member bearing on the mechanism to which connected symmetrically with reference to the axis of the suspending track member, whereby a load on the bridge will not rock the suspended mechanism in either direction, and power mechanism on the bridge member for driving the hoisting mechanisms.

5

10

RAGNAR A. NORBOM.
